UNITED STATES PATENT OFFICE.

PAUL J. FENSKE, OF MART, TEXAS.

RAIL-JOINT.

1,350,215.

Specification of Letters Patent. Patented Aug. 17, 1920.

Application filed April 5, 1920. Serial No. 371,316.

To all whom it may concern:

Be it known that I, PAUL J. FENSKE, a citizen of the United States, residing at Mart, in the county of McLennan and State 5 of Texas, have invented certain new and useful Improvements in Rail-Joints, of which the following is a specification.

This invention relates to improvements in railway rail joints, and has for one of its 10 objects to provide a device of this character in which the confronting ends of the rails are firmly united without the use of fish plates or clamping bolts, and in which the rail ends may be quickly and readily attached to or detached from each other.

Another object of the invention is to provide a device of this character wherein the rails are retained in alinement both laterally and vertically and wherein a continuous 20 tread is produced which obviates all jarring and jolting by the rolling stock.

Another object of the invention is to produce a joint which may be quickly assembled by any person without previous skill or 25 knowledge or by unskilled labor.

With these and other objects in view, the invention consists in certain novel features of construction as hereinafter shown and described and then specifically pointed out in 30 the claims, and in the drawings illustrative of the preferred embodiment of the invention.

Figure 1 is a side elevation of the abutting ends of a pair of railway rails embodying 35 the improved joint.

Figs. 2 and 3 are end views of the rails.

Fig. 4 represents the confronting portions of the rails separated and in position to be united.

40 Each rail includes a head or tread portion 10, a web portion 11 and a tie flange portion 12, of the ordinary standard pattern. The head portion of one rail is formed with a socket 13, while the head portion of the other rail is formed with a spur or stud 14 to engage in the socket when the rails are arranged to abut end to end.

The web portion 11 of one rail is formed with an upper curved seat or slot 15 and a 50 lower curved seat or slot 16, the latter extending at its inner end for a distance into the body of the tie flange portion 12, as shown.

By this means two tongues are produced, 55 one at 17 between the seats 15 and 16, and the other entirely within the body of the

flange 12 as shown at 18. The free end of the tongue 18, it will be noted, is of greater thickness than its "root" at the inner end of the seat 16, and with its inner face curved. 60

The confronting end of the web 11 of the other rail is formed with tongues 19 and 20 conforming to and adapted to engage in the seats 15 and 16, and with a downwardly opening recess or seat 21 to receive the 65 tongue 18. The upper and lower faces of the tongues 19 and 20 are curved to conform to the curvatures of the corresponding faces of the seats 15 and 16, but are less in length than the seats, as shown, to prevent binding. 70

The inner end of the seat 21 is cut away or inclined as shown at 22 to permit the rails to be disposed in the required position when uniting the rails, without cramping as 75 shown in Fig. 4.

At its transverse center, the tongue 20 is formed with a rib 23 which extends into the seat 22, while the tongue 18 is formed with a channel 24 directed longitudinally of the rail to receive the rib 23 when the rail ends 80 are united, and thus supplement the force exerted by the spur or stud 14, to resist lateral displacement.

The coacting seats 15 and 16, and tongues 17, 19 and 20 extend entirely through the 85 webs 11, and thus effectually resist vertical displacement, while the spur 14 and rib 23 coacting with the seat 13 and channel 24, effectually resist lateral displacement.

The improved device is simple in construction, and dispenses with the cumbersome and expensive fish or clamp plates and clamp bolts of the ordinary rail way rail joint.

The preferred embodiment of the invention is disclosed in the drawings and set forth in the specifications, but it will be understood that any modifications within the scope of the claims may be made in the construction without departing from the 100 principle of the invention or sacrificing any of its advantages.

I claim:

1. In a device of the class described, a rail joint comprising coacting rails abutting end to end, each including a head portion a web portion and a flange portion, the head portion of one rail having a socket and the head portion of the other rail having a spur engaging in said socket, the web portion of one rail having a plurality of downwardly curving sockets extending entirely therethrough 110

and the web portion of the other rail having tongues curved to correspond to and engageable in the curved sockets, and the flange of one rail cut away to form a tongue and the flange of the other rail having a downwardly opening recess to receive the terminal of the flange tongue.

2. In a device of the class described, a rail joint comprising coacting rails abutting end to end, each including a head portion, a web portion and a flange portion, the head portion of one rail having a socket and the head portion of the other rail having a spur en-

gaging in said socket, the web portion of one rail having a plurality of downwardly curving sockets extending entirely therethrough and the web portion of the other rail having tongues curved to correspond to and engageable in the curved sockets, and the flange of one rail cut away to form a tongue and the flange of the other rail having a downwardly opening recess to receive the terminal of the flange tongue.

In testimony whereof, I affix my signature hereto.

PAUL J. FENSKE.
